CARD PLAYING DEVICE

Charles R. Walgreen, Jr., Chicago, Ill., assignor
to Walgreen Co., Chicago, Ill., a corporation of
Illinois

Application January 20, 1934, Serial No. 707,518

14 Claims. (Cl. 273—151)

This invention relates to card playing devices and more particularly to card receptacles for playing duplicate bridge, although certain features thereof may be employed with equal advantage for other purposes.

It contemplates more especially the provision of a duplicate card playing device that is simple, compact, inexpensive and of novel construction.

10 The present invention that embodies an advance in duplicate bridge boards that present a means by which predetermined hands can be kept intact, thereby enabling any number of partners to play the same distribution of cards. This method of play permits a comparison of playing ability and eliminates the factor of either side winning because of a run of good cards.

One object of the present invention is to provide simple and improved card receptacles for 20 enabling duplicate card playing with the same distribution of cards.

Another object is to provide simple, compact and inexpensive card receptacles for duplicate card playing purposes.

25 Still another object is to provide duplicate card playing boards that have a plurality of card receptacles for retaining hands of a card deck in stacked relation—according to their original distribution.

30 A further object is to provide a bridge board that has a plurality of card receiving receptacles suitably marked for retaining originally distributed hands in stacked relation for duplicate playing.

35 A still further object is to provide a plurality of bridge boards that have a plurality of card receiving receptacles suitably marked for retaining originally distributed hands in stacked relation for duplicate playing of successive hands.

40 Still a further object is to provide a self-contained bridge board that is provided with a plurality of adjacently disposed receptacles for retaining originally distributed hands in stacked relation for duplicate playing of the same hands enabling card playing skill comparisons.

45 Other objects and advantages will appear from the following description of an illustrated embodiment of the present invention.

In the drawings:

50 Figure 1 is a perspective view of a device embodying features of the present invention.

Figure 2 is a sectional view taken substantially along line II—II of Figure 1.

55 Figure 3 is a sectional view taken substantially along line III—III of Figure 1.

Figure 4 is a sectional view taken substantially along line IV—IV of Figure 2.

Figure 5 is a development of the receptacle casing embodying features of the device described in Figure 1.

5 Figure 6 is a perspective view of an individual receptacle as confined within the casing shown in Figures 1 and 5.

Figure 7 is a similar view in perspective of an adjacent receptacle employed in connection with 10 the device shown in Figures 1 and 5.

Figure 8 is a plan view of four individual card playing receptacles for enabling duplicate playing of four separate hands of bridge or other card games.

15 Figure 9 is an end view in elevation of the device as shown in Figure 8.

Figure 10 is a perspective view of a device similar as shown in Figure 1 as taken from another angle, parts thereof being broken away to clarify 20 the showing.

The structure selected for illustration comprises a carton 10 stamped or otherwise shaped from sheet material such as cardboard to confine a plurality of card receptacles 11, 12, 13 and 25 14, in this instance four, which are sized and shaped to receive and retain independent hands of a card game where four individuals are involved. This device is primarily applicable to the game of duplicate bridge wherein the original distribution of cards usually involves four individuals with thirteen cards to each prior to commencing the first play. In consequence thereof, each carton 10 is capable of retaining and confining the individual hands or original 30 distribution of cards in stacked relation within the independent receptacles 11, 12, 13 and 14 in a manner that will appear more fully hereinafter.

35 The card confining device 10 may take innumerable shapes or involve various principles of card segregation, but a preferred form thereof consists in sheet material stamped or otherwise shaped to present the top surface 15 defined by parallel fold lines 16 and 17. The top surface 15 is contiguous with side walls 18 and 19 of a depth that will accommodate individual hands of playing cards in stacked relation. To this end, the blank of sheet material is provided with an additional pair of fold lines 20 and 21 in spaced parallelism with fold lines 16 and 17, respectively, to define the side 45 walls 18 and 19 contiguous with the top surface 15 of the carton 10.

50 Flaps 22 and 23 extend from the fold lines 20 and 21, respectively, so as to overlap each other in assembled folded relation to define the bottom 55

24 of the carton 10. The carton 10 is maintained in rigid assembled relation to preferably form a substantially rectangular configuration by applying any suitable adhesive to the adjacent surfaces 5 of the overlapping portions 25 of the bottom members 22 and 23. This will retain the receptacle casing 10 in rigid form-sustaining and form-retaining assembly to present the top 15, bottom 24, and side walls 18 and 19 intermediate and contiguous therewith.

10 The ends of the carton 15 are closed by means of flaps 26 and 27 formed contiguous with the top surface 15 of the carton blank 10, these being provided with intermediate fold lines 28 and 29, respectively, which are spaced from the top section ends 30 substantially for a distance equivalent with the spacing of the fold lines 20 and 21 from the top section fold lines 16 and 17. In consequence thereof, the end flaps 26 and 27 can be folded so as to present an end surface or walls 31 and 32 which serve as end closures for the carton 10 and the flaps 26 and 27 are folded along lines 28 and 29 for telescopic reception within the interior of the carton 10. To this end, the side walls 25 18 and 19 of the carton 10 are provided with extending side flaps 33 and 34 joined thereto by crease lines 35 and 36, respectively, so as to be folded inwardly prior to the telescopic engagement of the flaps 26 and 27 with the interior of 30 the carton 10 for total enclosure thereof.

35 With this arrangement of features, the blank 10 may be stamped in a single operation so as to form the outline and fold lines therein as above described, and the folded assembly thereof will result in a fully enclosed receptacle 10 that is provided with facilities for the representation of cards in stacked relation as will appear more fully hereinafter.

40 The length of the carton 10 in its folded assembled relation of the contiguous parts thereof, is such to accommodate a plurality of receptacles 11, 12, 13 and 14, in this instance four, which are disposed adjacent to each other. These receptacles 11 to 14 have an interior 37 of sufficient 45 length, width and depth to accommodate the desired number of cards to each hand, in this instance thirteen, for confinement independent of the carton 10 which merely serves to retain the receptacles 11 to 14 in the proper assembled relation. As shown, the receptacles 11 to 14 have a full-sized bottom 38 which extends for the width of the carton 10 with sides 39 and 40 coextensive therewith to fit within the chambered interior thereof.

55 The receptacle sides 39 and 40 terminate in a rear wall 41 which serves as a closure for one end thereof, there being a partial top member or closure 42 which extends, in this instance, for substantially seven-tenths ($\frac{7}{10}$) of the receptacle 60 length to provide full exposure from one end and top portion of the receptacles for convenient insertion and removal of the cards through the proper openings provided in the carton 10 which will appear more fully hereinafter. The rear wall 65 41 may be omitted as the carton serves as an end closure therefor.

70 It is to be noted that these receptacles 11 to 14 can be stamped or otherwise shaped from a single unitary sheet of material so as to present the proper fold lines and areas for assembly into independent receptacle units for card retention in 75 stacked relation. These receptacles 11 to 14 are disposed adjacently so that the end walls are in aligned contact for complete insertion within the carton 10. So that the interior of the receptacles

11 to 14 may be accessible from the exterior of the carton 10, the latter is provided with substantially rectangular openings 43, 44, 45 and 46, in this instance four, which are disposed alternately of each other in pairs for communication with each edge or fold lines 16 and 17 of the carton blank 10 (Figure 5). That portion of the substantially rectangular openings 43 to 46 which extends into the side walls 18 and 19 for a portion or substantially one-half the depth thereof, are provided with a substantially semi-circular opening 47 which extends into the bottom flaps 22 and 23 so as to register with correspondingly shaped openings 48 provided in the receptacles 11 to 14 inclusive, thereby enabling the cards 49 (Figure 15 15 10) confined in the receptacles to be lifted by insertion of the fingers from the bottom of the receptacle carton 10 so that the edges thereof may be grasped with the fingers of the attendant or player for removal.

20 In order to hold or retain the cards 49 within the receptacles 11 to 14, inclusive, as well as to hold these receptacles in their assembled relation, flaps 50 are formed in the top section 15 of the carton 10 from the cut out regions 43, 44, 45 and 46 provided therein as described supra. The flaps 50 are provided with fold lines 51 so as to present a flap extension 52 which abuts against the cards 49 to retain such against accidental movement and to confine these cards 49 against displacement when the receptacle 10 is moved around or handled by the player or players. In order that the end receptacles 11 and 14 may be removed from the edges 30 of the receptacle carton 10, these receptacles 11 and 14 are provided with a bottom extension 53 which spaces the end cartons 11 and 14 from the ends of the receptacle carton 10 and still precludes lateral movement so as to retain all the receptacles 11 to 14 in fixed relation to preclude misalignment with the corresponding openings 43, 44, 45 and 46 provided in the carton receptacle 10.

30 It is thus apparent that a full deck of cards can be retained in stacked relation in accordance with their original distribution to each player so that a duplicate hand may be played with the parties interchanged to compare their skill and playing with the same hand or card distribution. Any number of such receptacle cartons 10 may be provided in this instance four (Figure 8), which 40 are properly marked and have each receptacle designated by indicia 54 which enables noting which players possessed the original distribution of cards so that they may be interchanged and have each team or pair or partners utilize the 45 same distribution of cards that was previously played by the other pair of partners or team.

General description of boards

55 All boards are provided with four spaces or receptacles large enough to hold a hand of thirteen cards. Each board has an arrow which should point to the north or a predetermined north direction regardless of which board is being played. Each board is stamped with the word "dealer" 60 which indicates which player has dealt the cards. For use in contract, the boards are printed with a phrase indicating which players are vulnerable. With each set is a strip of numbers. Cut out the numbers starting with one and paste the number on the end of the board as an identification 65 of that particular board as shown in Figure 9.

Preparing for playing duplicate bridge

70 Decks of cards equal in number to the boards to 75

be used are dealt into four hands of thirteen cards and each hand is placed into a compartment or receptacle in the board.

Playing

The first board is placed in the center of the table with the arrow pointing north or a designated north. The player receiving the hand marked dealer is the first bidder and the bidding proceeds as in regular bridge or contract. This procedure continues through any given number of boards and then partners East and West change seats with North and South and play through the same number of boards. Duplicate differs from regular bridge in playing the cards in that the players do not jumble their cards in the center of the table. Instead each player in turn places his card face up in front of him near the board that is the center of the table. As soon as the winner of the trick has been determined each player including the dummy takes back his card and places it face down near his edge of the table and scores winning and losing tricks as follows:

Partners winning a trick place the cards face down with the long dimension of the cards pointing to each other.

Partners losing a trick place the cards face down with the long dimension of the cards pointing to opponents.

The cards can be overlapped or booked to conserve space. Partner's count of winning and losing tricks should check and also may be checked with opponents.

Upon completion of the hand each player gathers his hand and places it back into its correct position in the board.

Scoring

In duplicate bridge or contract the system of playing rubbers is not used. A bonus is acquired by making game in one hand. In auction, score a bonus of 125 for making game in one hand. In contract, score a bonus or 500 for game bid made in one hand if vulnerable and 300 for game bid made in one hand if invulnerable. These rules are, of course, arbitrary and applicable to the particular game that is played. The duplicate bridge boards or carton receptacles enable the compact retention of cards in accordance with their original distribution to avoid error, mistake, and convenient resort thereto for duplicate playing.

Various changes may be made in the embodiment of the invention herein specifically described without departing from or sacrificing any of the advantages of the invention as defined in the appended claims.

I claim:

1. In a card playing device of the character described, the combination with a substantially rectangular body member, of a plurality of rectangular receptacles adjacently disposed transversely in the same plane for confinement by said body member, said receptacles having end openings for communication with one or the other sides of the body member for receiving and retaining the cards of each player in stacked relation in accordance with their original distribution, and means for differentiating each receptacle from the other to distinguish and designate the cards for each original player.

2. In a card playing device of the character described, the combination with an elongated rectangular body member, of a plurality of rectangular receptacles adjacently associated in the

same plane for transverse confinement in said body member, there being openings in said body member to communicate with the interior of said receptacles for receiving and retaining the cards of each player in stacked relation, and means on said body member for differentiating each receptacle from the other to distinguish and designate the cards for each original player.

3. In a card playing device of the character described, the combination with an elongated rectangular body member, of a plurality of card receptacles provided transversely in said body member to adjacently extend for the entire width thereof, there being openings alternately disposed along the sides of said body member to communicate with the interior of said receptacles for receiving and retaining the cards of each player in stacked relation, and means for differentiating each receptacle from the other to distinguish and designate the cards for each original player.

4. In a card playing device of the character described, the combination with an elongated rectangular body member, of a plurality of separate open-end receptacles disposed transversely in the same plane within said body member, said receptacles being in adjacent relation so that their open-ends are alternately arranged relative to each other, there being openings in said body member to communicate with the interior of said receptacles through the open-ends thereof for receiving and retaining cards in stacked relation in accordance with their original distribution, and means for differentiating each receptacle from the other to distinguish and designate the cards for each original player.

5. In a card playing device of the character described, the combination with an elongated rectangular body member, of a plurality of rectangular open-end receptacles transversely associated adjacent each other within said body member, there being openings in said body member to communicate with the interior of said receptacles through the open ends thereof for receiving and retaining cards in stacked relation, said receptacles being transversely arranged so that their open-ends are alternately disposed in opposed directions within said body member to enable their more compact association, and means for differentiating each receptacle from the other to distinguish and designate the cards for each original player.

6. In a card playing device of the character described, the combination with a body member of a plurality of separate open-end receptacles removably associated with said body member for retaining the cards of each player in stacked relation in accordance with their original distribution, there being openings in said body member to communicate with the interior of said receptacles, said receptacles being transversely arranged so that their open-ends are alternately disposed in opposed directions, and flaps extending from said body member openings for registry with the open-end of said receptacles to retain the contents against accidental removal.

7. In a card playing device of the character described, the combination with a body member of a plurality of separate open-end receptacles removably associated with said body member for retaining the cards of each player in stacked relation in accordance with their original distribution, there being openings in said body member to communicate with the interior of said receptacles, said receptacles being transversely arranged so that their open-ends are alternately

disposed in opposed directions, and flaps extending from said body member openings for registry with the open-end of said receptacles, said flap having an extension for projection into said receptacles to retain the contents against accidental removal.

8. In a card playing device of the character described, the combination with a body member of a plurality of separate open-end receptacles removably associated with said body member for retaining the cards of each player in stacked relation in accordance with their original distribution, there being openings in said body member to communicate with the interior of said receptacles, said receptacles being transversely arranged so that their open-ends are alternately disposed in opposed directions, and flaps extending from said body member openings for registry with the open end of said receptacles, said flap having a fold line connected extension for projection into said receptacles to retain the contents against accidental removal.

9. In a card playing device of the character described, the combination with a body member of a plurality of separate open-end receptacles removably associated with said body member for retaining the cards of each player in stacked relation in accordance with their original distribution, there being openings in said body member to communicate with the interior of said receptacles, said receptacles being transversely arranged so that their open-ends are alternately disposed in opposed directions, and flaps extending from said body member openings for registry with the open end of said receptacles, said flap having a fold line connected extension for projection into said receptacles to retain the contents against accidental removal.

10. In a duplicate card playing device, the combination with a unitary blank having fold lines impressed therein to define a foldable carton, and flaps formed on said blank to effect end enclosure thereof into a substantially rectangular carton, of a plurality of open-end card receiving receptacles confined within said carton prior to the end-flap folding thereof, there being openings provided in said carton blank for registry with the open ends of said receptacles.

11. In a duplicate card playing device, the combination with a unitary blank having fold lines impressed therein to define a foldable carton, and flaps formed on said blank to effect end enclosure thereof into a substantially rectangular carton, of a plurality of open-end card receiving receptacles confined within said carton prior to the end-flap folding thereof, there being open-

ings provided in said carton blank for registry with the open ends of said receptacles, and flaps extending from an edge of said carton openings for registry with the open ends of said receptacles.

12. In a duplicate card playing device, the combination with a unitary blank having fold lines impressed therein to define a foldable carton, the flaps formed on said blank to effect end enclosure thereof into a substantially rectangular carton, of a plurality of open-end card receiving receptacles confined within said carton prior to the end-flap folding thereof, said receptacles being transversely arranged so that their open-ends are alternately disposed in opposed directions, there being openings provided in said carton blank for registry with the open ends of said receptacles, and flaps extending from an edge of said carton openings for registry with the open ends of said receptacles.

13. In a duplicate card playing device, the combination with a unitary blank having fold lines impressed therein to define a foldable carton, and flaps formed on said blank to effect end enclosure thereof into a substantially rectangular carton, of a plurality of open-end card receiving receptacles confined within said carton prior to the end-flap folding thereof, said receptacles being transversely arranged so that their open-ends are alternately disposed in opposed directions, there being openings provided in said carton blank for registry with the open ends of said receptacles, flaps extending from an edge of said carton openings for registry with the open ends of said receptacles, and extensions in folded connection with said opening flaps for projection into said receptacles to retain the contents thereof against accidental removal.

14. In a duplicate card playing device, the combination with a unitary blank having fold lines impressed therein to define a foldable carton, and flaps formed on said blank to effect end enclosure thereof into a substantially rectangular carton, of a plurality of open-end card receiving receptacles confined within said carton prior to the end-flap folding thereof, said receptacles being transversely arranged so that their open-ends are alternately disposed in opposed directions, there being openings provided in said carton blank for registry with the open ends of said receptacles, flaps extending from an edge of said carton openings for registry with the open ends of said receptacles, and extensions in folded connection with said opening flaps for projection into said receptacles to retain the contents thereof against accidental removal.

CHARLES R. WALGREEN, JR. 60
